(57) **CLAIM**

The ornamental design for a loudspeaker for electronic device with line-in connector, as shown and described.

DESCRIPTION

FIG. 1 is a perspective view of a loudspeaker for electronic device with line-in connector in accordance with my design; FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view thereof, with electronic device;

FIG. 9 is a perspective view of a second embodiment of FIG. 1;

FIG. 10 is a perspective view of a third embodiment of FIG. 1; and,

FIG. 11 is a perspective view of a fourth embodiment of FIG. 1.

The broken lines showing on FIGS. 1-3, FIGS. 6-11 are for illustrative purposes only and form no part of the claimed design.
